BRASSIÈRES

David Haimoff, Los Angeles, Calif., assignor, by
mesne assignments, to Sho-Form Brassières,
Inc., Los Angeles, Calif., a corporation of Cali-
fornia

Application January 17, 1934, Serial No. 707,021

2 Claims. (Cl. 2—42)

This invention relates generally to the class of apparel, and same is more particularly directed to certain new improvements in brassières.

An object of the invention is to provide a brassière characterized by means which affords a comfortable yieldable support for the breasts and which functions in a highly efficient and desirable manner to prevent abrasion of the skin, which heretofore in such articles unavoidably resulted from an application of injurious binding and cutting stresses or forces upon the breasts.

A further object is to provide means for use in cases where the skin tissues and ligaments have been broken down with a resulting falling of the breasts, which said means will afford maximum comfort to the wearer and serve to raise the breasts to their more normal positions.

Another object is to provide a brassière whose breast supports are each characterized by a plurality of complementary sections which mutually function to produce a breast receptacle, the shape of which is accurately breast-like in all essential respects.

A further object is to provide a brassière which will yieldingly exert an upward lift upon the breasts through the embodiment of means that will be wholly invisible when the brassière is worn beneath evening dresses, the backs of which are low-cut.

Referring now to the accompanying drawing for a better understanding of my invention,

Figure 1 is a view substantially in front elevation of the brassière showing same applied;

Figure 2 is a view substantially in rear elevation of the brassière showing same applied;

Figure 3 is a section on the line 3—3 of Figure 1;

Figure 4 is a fragmentary view illustrating a detachable connection embodied in the brassière;

Figure 5 is a perspective view looking at the brassière from the rear.

In carrying the invention into practice, I employ a brassière consisting of a body member 5 including a front piece 6 and back pieces 7—7. These several pieces may be constructed of any suitable well known fabric material, such as satin. The back pieces 7—7 are substantially triangular and the small free end 8 of each thereof has secured thereto one end of an elastic tape 9. On reference to Figure 2 of the drawing, it will be noted that the tape 9 at the right hand side passes through the slot 10 of a tape guide 11, and the end 12 of the tape extends to a point in advance of the end 8 and same is secured by stitching to the lower edge of the member 5. The tape 8 at

the left hand side passes through the slot 13 in said tape guide and the end 14 of this tape is provided with a hook 15 which has detachable connection with an eye 16 (Figure 4), the latter secured to the member 5 at a point in advance of the opposite end of said tape, whereby to permit the member to be readily adjusted so that it may be passed over the head and operatively adjusted to the person of the user. The said tape guide 11 is formed with a horizontal slot 16 through which is looped one end of a tensioning tape 18, the latter preferably formed of inelastic material. The lower end of this tensioning tape is provided with means 19 adapted to be detachably secured at the waist line to a corset or some other form of undergarment, whereby movement in an upward direction will be imparted to the member 5 for a purpose to be hereinafter set forth.

The front piece 6 is provided with breast supports 20 which may be formed of lace or other suitable soft material. The lower marginal edges of these supports are stitched to said front piece. Adjustable shoulder straps 21 connect the said breast supports with the back pieces 7, and it thus follows that when pull in a downward direction is exerted upon the tape 18 the front of the brassière will be elevated. The front and back pieces 6 and 7 of the body member 5 are suitably lined, such as with net, and secured to the inner face of the front piece 6 and substantially following the marginal portions of the supports are crescent-shaped pieces or saddles 22 whose upper edges are faced with elastic tape material 23. These pieces 22 are formed with a fullness so that they may stretch longitudinally when the tape 23 is respectively stressed and relaxed. The said pieces 22 are of such width that by being shaped and disposed in the positions aforementioned they define with the supports 20 arcuate pockets to receive the lower portions of the breasts. It follows that because of the construction last stated, a vertical lift will be imparted to the breasts from beneath same after the article has been adjusted to the person and the tape 18 connected with the corset or other undergarment. When the tape 18 is pulled in a downward direction, it stretches the tapes 9 so that when the brassière is used with a dress the back of which is low cut, said tapes will not be visible to the eye. The arrangement of parts employed is thus not only such as will impart a vertical lifting motion to the bust supports 20 and, incidentally, conceal the tapes 9 from view, but, I have provided effective means for yieldingly supporting the breasts in a manner that will result in the greatest com-

fort to the user. The general construction of the article is also such as to prevent cutting or abrading of the breasts.

In order that the brassière may be as nearly form-fitting as possible, the supports 20 are each formed of a plurality of substantially similar sections 20a, each of which, in profile, is breast-shaped. In the form herein illustrated, I employ four such sections, and the side edge portions of one section are stitched to the like edge portions of the adjacent or complementary sections.

The lower edge of the front piece 6 is gathered at 6a along a vertical line drawn between the supports 20 and this gathered edge is made elastic by the application of a suitable length of rubber tape 6b. This readily allows for expansion and contraction of the brassière to compensate for like movements of the chest of the user or when breathing.

20 The shoulder straps 21 should, of course, be of inelastic material such as a suitable grade of silk or satin ribbon. When a downward pull is applied to the elastic tapes 9, it follows that the shoulder straps may freely slide across the shoulders in order that the intended lift may be transferred to the supports 20. The tapes 9, like the tapes 23, should be constructed of a good grade of rubber but the tapes 23 should be more delicate or more readily capable of being stretched than the tapes 9.

What is claimed is:

1. A garment comprising a body member of a form to partly embrace the body above the waist line and including breast supports, each support including a substantially crescent-shaped saddle portion at its lower marginal edge, the same formed of soft material with a fullness to enable same to be stretched and being faced by an elastic tape so as to gather in said fullness and enable said portion to yield when pull in an upward direction is applied to the body member, shoul-

der straps connected with the supports, back pieces of substantially triangular form secured to the body member at the opposite sides thereof and secured at their upper edges to the lower ends of said shoulder straps at the back of the garment, a tape guide in back of the garment, elastic tapes complementary to each triangular back piece and each being attached to said guide and having two angularly related branches terminally secured to a complementary back piece, and means for connecting the guide with a waist line garment to tension the elastic tapes and to exert an upward pull upon the body member and thus cause a lifting of the breasts and for yieldingly stressing the saddles to cause same to snugly embrace the breasts throughout the lengths of the saddles.

2. In a brassière, a body embracing member having means for supporting same from the shoulders, said member including a front piece 20 having breast receiving and supporting cups, each provided with a substantially crescent shaped saddle at its lower marginal edge, in partial embracing relationship to the breast and constructed of soft material having a fullness to enable same to be stretched by the supported weight of the breast and/or when pull is applied to the embracing member in a direction to lift the breasts, each of said saddles having embodied in the construction thereof a rubber element to enable the saddle to be stretched in response to the supported weight of the breast and/or when pull in said upward direction is applied to said embracing member; and means for exerting the aforementioned upward pull upon said embracing member, said body embracing member having a circumferentially expandable and contractible portion medially of the front and at the bottom of the member adapted to yieldingly compensate for upward pull upon said member.

DAVID HAIMOFF.
